ROOTER ATTACHMENT FOR BULLDOZERS

Carl D. Forte, Los Angeles, Calif.; Helen A. Forte, administratrix of said Carl D. Forte, deceased, assignor to said Helen A. Forte

Application February 7, 1955, Serial No. 486,463

6 Claims. (Cl. 37—145)

My invention relates to rooter attachments for bulldozers, and it has for a purpose the provision of a rooter attachment which is structurally characterized by its simplicity, low cost of manufacture, and durability to successfully withstand the rough usage to which it is put; and functionally characterized by the easy mode of adjustment of an adapter to fixedly secure the attachment to and in operative position on the moldboard of a bulldozer to lock it against movement in any direction thereon.

Also a purpose is to provide a rooter attachment embodying a standard on the upper end of which is mounted a bracket carrying the adapter, the bracket being adjustable on the standard and the adapter bodily adjustable on the bracket to the common end of enabling the rooter attachment to be applied to and firmly secured on a moldboard irrespective of the width and inclination of the angle bar on the rear side of the top edge of the moldboard.

A further purpose of my invention is the provision of an adapter which includes a member of hook form that is pivoted on the bracket and adjustable by a screw member not only to embrace the moldboard angle bar, but to move the bracket so as to cause the standard to be pulled against the moldboard and to simultaneously elevate the standard on the moldboard in such manner as to bring the saddle of the shank carried by the standard into firm gripping engagement with the blade on the lower edge of the moldboard, and thus to effectively lock the attachment in operative position on the moldboard.

Another purpose is to provide in a rooter attachment a bracket which is mounted on the standard to occupy an inactive position which permits application of the attachment to a moldboard, and an active position in which the adapter can be brought into engagement with the moldboard angle bar and subsequently adjusted to lock the entire attachment in operative position on the moldboard.

I will describe only one form of rooter attachment embodying my invention in its association with one form of bulldozer moldboard, and will then point out the novel features thereof in claims.

In the accompanying drawings:

Fig. 1 is a view showing in end elevation the forward part of a bulldozer and having applied to the moldboard thereof one form of rooter attachment embodying my invention.

Fig. 2 is an enlarged side elevational view of the rooter attachment with a portion thereof in section.

Fig. 3 is a vertical sectional view taken on the line 3—3 of Fig. 2.

Fig. 4 is an enlarged top plan view of the attachment.

Fig. 5 is an enlarged vertical sectional view taken on the line 5—5 of Fig. 2.

Fig. 6 is an enlarged vertical sectional view taken on the line 6—6 of Fig. 2.

Referring more particularly to the drawings, the rooter attachment of my invention comprises a shank K hav-

2

ing a flat portion 14 on the forward edge of which is a front longitudinal flange 15, and on the rear edge of which is a longitudinal rear flange 16. At the lower end of these flanges the shank merges into a transversely widened portion 17 at the rear side thereof which is formed with a longitudinal groove 18 that is V-shaped in cross section and inclined downward and forward as shown in Fig. 2. The portion 17 and the slot 18 coact to provide a saddle T which is adapted for the reception of the blade of the moldboard of a bulldozer, as will be described hereinafter.

As is usual in such rooter attachments, the lower end of the shank K where it depends from the saddle T is exteriorly tapered and interiorly formed with a socket 19 in which the tongue 20 of a digger tooth 21 is received and secured by a pin 22.

The upper portion of the shank K is received in a standard S which is of sleeve form and rectangular in cross section. The shank K is capable of adjustment longitudinally in the standard S and can be secured in any position of adjustment in order that the attachment as a whole can be applied to bulldozer moldboards of various widths or heights. The means for securing the shank K in longitudinally adjusted position comprises, in the present instance, a series of openings 23 formed in registering pairs in the side walls of the standard, a series of recesses 24 in the rear flange 16, and a locking pin 25 which can be extended through any pair of openings to engage within any one recess and thereby secure the shank in any desired longitudinal position of adjustment in the standard.

It will be noted that the recesses 24 are staggered in relation to the openings 23 in order that a fine degree of adjustment of the shank can be attained. As shown in Fig. 3 the pin 25 has a faceted head 26 on one end and a cotter pin 27 extending through the other end which when removed permits withdrawal of the pin from the standard to be reinserted in another pair of openings 23 or another recess 24 for securing another adjustment of the shank in the standard.

On the upper end of the standard S is mounted a bracket B which is made up of a pair of arms 28 in the form of elongated plates having rounded ends. This bracket is so mounted on the standard that it extends rearwardly thereof at an angle thereto and it is susceptible of angular adjustment with relation to the standard for a purpose to be described hereinafter.

The means by which the bracket can be adjusted angularly comprises a pivot pin 29 and a holding pin 30. The pin 29 extends through one end of the arms 28 and through ears 31 formed on the standard S. The pin 29 may be provided at one end with a lock nut 32 to prevent accidental displacement of the pin from the ears and the arms. The holding pin 30 extends through registering openings in the arms 28, and engages within either of a pair of recesses 33. These recesses are formed in a rearwardly extending portion 34 of a rear wall of the standard S, and they are on different radii with respect to the center of the ears 31 so that accordingly as the holding pin 30 engages within one recess or the other the angular position of the bracket on the standard is varied. The pin 30 may be of the same construction as the pivot pin 29.

For securely clamping the attachment in operative position on the moldboard of a bulldozer, an adapter A is provided which comprises a hook or arcuate member 35 preferably of T-form in cross section and provided at its free end with an arcuate head 36. The other end of the hook is provided with an integral arm or extension 37. At the junction of the arm and hook a bearing sleeve 38 is formed through which extends a pivot pin 39. This

pin also extends through the arms 28 and is secured therein by means of a nut 40 and cotter pin 41.

It is by means of this pin 39 that the hook and arm are mounted for pivotal movement between the bracket arms 28 so that it can be moved to that adjusted position about the pin to cause the hook to have clamping engagement with the upper part of a moldboard. The hook can be moved to and secured in the required adjusted position by means of an element E which is adjustable in the free end of the arm 37. This element comprises a screw 42 adjustable in a screw threaded sleeve 43 on the free end of the arm 37. At one end the screw is formed with an integral and faceted head 44, and at the other end with a ball 45 received in a socket 46 of a foot 47 which is preferably flat.

In Fig. 1 is shown a conventional moldboard M of a bulldozer, and it is provided at its lower end with a blade D. To the rear side of the moldboard adjacent the upper edge thereof is secured an angle bar F and in such manner that one part 48 thereof is inclined downwardly from the upper edge of the moldboard and the other part 49 inclined upwardly and rearwardly from the rear side of the moldboard.

To fixedly mount the rooter attachment in operative position on the moldboard M, the rooter is first stood upright with the tooth 21 partly penetrating the ground and the bracket B in the inactive position shown in broken lines in Fig. 1. Movement of the bracket from the active position shown in solid lines in Fig. 1 to the inactive position is made possible by removal of the holding pin 30 thus allowing the bracket to be swung on the pivot pin 29 to such inactive position.

With the attachment so positioned the bulldozer is advanced toward the rooter with the moldboard lowered to a position such that the blade D can pass into the groove 18 of the saddle T. As the blade passes into the saddle the rooter is tilted rearwardly to bring the standard S against the moldboard, whereupon the operator swings the bracket from inactive to active position and secures it in place by inserting the holding pin 30 into one recess 33 or the other to dispose the adapter A so that it can be moved into clamping engagement with the bar F.

Movement of the adapter to bar clamping position is effected by swinging the hook 35 downwardly about the pivot 39 so that the head 36 is brought into contact with the part 49 of the angle bar, and the foot 47 into contact with the upper side of the bar part 48. By now feeding the screw 42 downwardly in the sleeve 43 an upward force is exerted on the arm 37 to rotate the hook 35 downwardly and forwardly to bring the head 36 into firm engagement with the bar part 49 and thereby firmly clamp the hook to the bar.

Concurrently with this operation of the adapter the screw 42 functions to exert an upward pressure on the bracket to elevate the standard S in the shank K and thereby force the saddle T into firm clamping relation to the blade D. As a consequence the rooter is securely clamped in operative position on the moldboard against movement in any direction even when subjected to the various forces resultant of use of the rooter by the bulldozer. Since the groove 18 is of V-form in cross section it is capable of receiving and by a wedging action securing the blade D thereto irrespective of the angle at which the blade is mounted on the moldboard.

It is desirable that the lower edge of the bracket B be substantially parallel to the bar part 48 in order that the screw 42 will be positioned substantially perpendicular to such bar part to actuate the adapter and lift the bracket. Since the angle of the bar part 48 may vary on different moldboards the bracket B can be adjusted on the standard S so that it will occupy a position parallel to the bar part irrespective of its angle through the medium of the holding pin 30 and the recesses 33 as will be understood.

Also to compensate for variation in the width and angle of the bar part 49 on different moldboards, so that the adapter may have proper clamping engagement with such part, the arms 28 of the bracket are provided with a series of openings 50 in any pair of which the pivot pin 39 is receivable to afford adjustment of the adapter longitudinally on the bracket.

Although I have herein shown and described only one form of rooter attachment embodying my invention, it is to be understood that various changes and modifications may be made therein without departing from the spirit of the invention and the spirit and scope of the appended claims.

What I claim is:

1. A rooter attachment for the moldboard of a bulldozer, including: a tooth-carrying member having a saddle thereon; a bracket mounted on the upper end of said member; and an adapter including a hook having an arm pivoted on the bracket, and an element adjustable on the arm at that side of the arm pivot opposite from the hook and which is adapted to bear on the upper part of the moldboard so that by adjustment thereof toward said part the hook is actuated to clamp the latter and the bracket simultaneously lifted to cause the saddle to embrace the lower part of the moldboard.

2. A rooter attachment for the moldboard of a bulldozer, including: a tooth-carrying member having a saddle thereon; a bracket mounted on the upper end of said member; coacting means on the upper end of said member and between the ends of the bracket affording angular adjustment of the latter so that its lower side can be positioned in a plane substantially paralleling the upper part of the moldboard; and an adapter including a hook having an arm pivoted on the bracket, and an element adjustable on the arm at that side of the arm pivot opposite from the hook and which is adapted to bear on the upper part of the moldboard so that by adjustment thereof toward said part the hook is actuated to clamp the latter and the bracket simultaneously lifted to cause the saddle to embrace the lower part of the moldboard.

3. A rooter attachment for the moldboard of a bulldozer, including: a tooth-carrying member having a saddle thereon; a bracket mounted on the upper end of said member coacting means on said member and the bracket affording angular adjustment of the latter so that its lower side can be positioned in a plane substantially paralleling the upper part of the moldboard; and adapter including a hook having an arm pivoted on the bracket; and an element adjustable on the arm at that side of the arm pivot opposite from the hook and which is adapted to bear on the upper part of the moldboard so that by adjustment thereof toward said part the hook is actuated to clamp the latter and the bracket simultaneously lifted to cause the saddle to embrace the lower part of the moldboard; and coacting means on the bracket and the adapter affording adjustment of the adapter longitudinally on the bracket so that the adapter is applicable to the upper part of moldboards of various sizes.

4. A rooter attachment for the moldboard of a bulldozer, including: a tooth-carrying member having a saddle thereon; a bracket comprising a pair of spaced arms at opposite sides of and pivoted at one end on the upper end of said member to occupy an inactive position in which it extends upwardly from said member, and an active position in which it extends at an angle to the rear of said member; coacting means on said member and the bracket for releasably securing the latter in active position; and an adapter including a hook having an extension pivoted on and between the bracket arms at that side of the pivot point of the latter opposite from the coacting means, and a screw threaded in the extension at that side of its pivot opposite from the hook, and which when the bracket is in active position is adapted to bear on an upper part of a moldboard so that

by adjustment thereof toward said part the hook is actuated to clamp the latter and the bracket simultaneously lifted to cause the saddle to embrace the lower part of the moldboard.

5. A rooter attachment as embodied in claim 4 wherein the coacting means is adjustable to secure the bracket at various angles when in active position, and comprises pairs of recesses in the rear portion of said member, and a pin extending through said arms and one pair of recesses.

6. A rooter attachment for a bulldozer moldboard having an angle bar secured to the rear side adjacent the upper edge thereof, and a blade secured on the lower edge thereof, including: a tooth-carrying member having a saddle thereon; a bracket comprising a pair of arms pivoted at one point on the upper end of said member to occupy an inactive position in which it extends upwardly from said member, and an active position in which it extends at an angle to the rear of said member; coacting means on said member and said bracket for 15 releasably securing the latter in a fixed active position; and an adapter including a hook having an extension pivoted on and between the bracket arms, and a screw

threaded in the extension at that side of its pivot opposite from the hook, and which is adapted to bear on the upper side of the angle bar so that by adjustment of the screw toward the angle bar the hook is actuated to embrace the lower rear side of the angle bar, and the bracket simultaneously lifted to cause the saddle to embrace the blade of the moldboard.
